UNITED STATES PATENT OFFICE.

CHARLES H. ATKINS, OF SPRINGFIELD, MASSACHUSETTS.

PAPER-MAKING APPARATUS.

1,120,433.

Specification of Letters Patent.

Patented Dec. 8, 1914.

Application filed June 24, 1912. Serial No. 705,358.

To all whom it may concern:

Be it known that I, CHARLES H. ATKINS, a citizen of the United States of America, residing at Springfield, in the county of 5 Hampden and State of Massachusetts, have invented new and useful Improvements in Paper-Making Apparatus, of which the following is a specification:

This invention relates to revolving suction 10 rolls for paper machines. It is especially adapted for use in cylinder machines, but it is not limited to this specific use, since it can be used efficiently on Fourdrinier machines and in many other connections.

15 The invention generally is adapted to embody a suction roll, preferably rotating, around which the paper is passed through part of a revolution together with its carrying medium as felt in a cylinder machine or 20 wire in a Fourdrinier machine. In the passage of the paper around the roll for a considerable arc means for extracting the water from the paper is provided and this means is so arranged that it operates on a large 25 area of the paper instead of a comparatively small area as has heretofore been the necessary practice in suction rolls. Applicant preferably moves the paper and roll together the former being held to the latter 30 by suction which extracts the water. In this operation considerable difficulty in transferring the paper to the roll and taking it from the roll without injury or breakage is experienced for the passage of 35 a light medium as paper to and from areas of largely changing pressure is a serious problem. Applicant has overcome the difficulties involved by providing means where the paper enters on the apparatus and where 40 the paper leaves the apparatus to cause the ready passage of the paper in the manner desired. In addition to the advantage obtained in having the paper pass to and from the roll properly other advantages are obtained 45 by the means mentioned as for instance the doing away with one carrying felt heretofore necessary in cylinder machines.

The object of applicant's invention is to provide an improved apparatus of the class 50 mentioned which will operate successfully and have a great capacity for extracting water from paper as it is made.

Other objects of the invention will appear 55 in the detailed description and annexed claims.

In the drawings forming part of this ap-

plication;—Figure 1 is a diagrammatic view of a cylinder machine showing the apparatus as positioned with respect to the other elements embodied in the complete apparatus necessary for manufacturing paper. Fig. 2 is a partial longitudinal sectional view of about half of the apparatus taken on line 2-2 of Fig. 3. Fig. 3 is a sectional view on line 3-3 of Fig. 2.

60 Referring to the drawings, Fig. 1, a^1 , a^2 , a^3 , a^4 , and a^5 represent tanks in which the paper is contained. A roll b in each tank picks up the paper stock therein and transfers a certain amount of it to the lower face 65 of a carrying felt d . The roll c forces the felt d against the face of the rolls b , in the usual manner, said roll c being regulated in the manner indicated. The felt d travels against the face of each roll b in the series 70 of tanks, as indicated, and when it leaves the last tank it contains a layer of paper sufficient in quantity to form the paper desired. The felt then turns on the roll c of the last roller and passes through a series of 75 guiding rollers h to the suction roll g . The felt passes around the guide-roller l with the paper next to that roll and then passes around the suction roll or cylinder g for a part of a rotation thereof having the felt 80 next to this roll and then leaves said roller g and passes to farther guide-roller l' . During the passage of the felt around the roll g a great quantity of water (in proportion to the whole quantity contained by the paper) 85 is abstracted therefrom in a manner to be described. The felt d carries the partially dried paper to the press roll k , where it leaves the paper and starts on its return travel to the pulp cylinders for the described 90 operation to be repeated. The paper, which is now strong enough to travel from roll to roll unsupported, passes to the roll p and then to the drying cylinder o , after which it 95 is treated in the usual manner.

100 In the operation of manufacturing paper, as described with this invention, it is usually only necessary to abstract the water from the wet pulp at one main point; that is, at the position of the roll g . If desired, 105 however, a series of such rolls may be used or the same may be used together with apparatus heretofore used. This apparatus as illustrating one way in which the invention can be carried out will now be specifically 110 described.

The large suction roll g is mounted to

rotate on the horizontal supporting pipe *u* on suitable bearings *y*. A stuffing box *C* is provided at each end to prevent communication between the atmosphere and the interior of the roll except through the perforations in the latter. The horizontal supporting pipe *u* is mounted at each end of the apparatus by the end frame pieces *A*. To this horizontal supporting pipe *u* is fastened a dependent casting *z* which extends the whole length of the suction roll, as indicated, and is of a suitable width for a purpose to be described. To the outer edge of this casting *z* is fastened a diaphragm *v*, the other edge of which is held by another casting *a* which latter is adapted for a purpose to be discussed. This casting *a* has two longitudinal side pieces which bear with a corresponding surface directly against the inner face of the roll *g* through the entire length thereof, as indicated in Figs. 2 and 3. These side pieces are of sufficient width to a little more than cover all the perforations of the suction roll along two longitudinal strips of said roll.

Referring to Fig. 3, the guide rollers *l* and *l'* are similarly constructed. They rotate on suitable bearings *y* which are supported by the horizontal pipe *n*, the latter being held by the two end frame pieces *A* previously mentioned as supporting the horizontal pipe *u*. A long narrow box-shaped casting *q* rests against the inner face of each guide-roll through the entire length thereof, as indicated in Fig. 2. This box-like structure has a communication with the pipe *n* through a conduit *r* which slides in a suitable pocket of the pipe *n* as indicated in Figs. 2 and 3. The only difference between these two guide-rolls is that one has the box-like structure pressing against the inner face of the guide roller where the outer face thereof is tangent to the suction roll, while the other box-like structure in the other guide-roll presses against the inner face thereof at a point distant from the tangent point. It is necessary to use the spring *s* in the first mentioned case to keep the box-like structure pressed against the inner face of the guide-roll *l*, while in the second case the weight of this box-like structure gives the proper pressure for the purpose desired.

As previously described, the felt carrying the paper enters on the roll *l* and passes around said roll to the point of tangency with the suction roll, after which it follows the periphery of that roll around the greater part of its circumference until it reaches the point of tangency of the guide roller *l'*, where it follows said roll and leaves the same at the point where the box-like structure *q* is bearing against the inner face of said roll. In this travel of the felt with the paper, the apparatus operates as

follows: In passing around the roll *l* the paper is next to the roll, but as the felt carries the paper to the suction roll *g* the paper is on the outside of the felt and the felt is next to the roll. In the passage of the paper from the roll *l* to a position on the roll *g* it is likely to tear or lap on the roll *l*, thus destroying the paper at that point. To prevent this the box-like structure pressing against the inner face of the perforated roll *l* is provided. Referring to Fig. 3, air, under pressure, is forced into the pipe *n* which air passing up the conduit *r* enters the box-like structure *q* pressing against the inner face of the guide-roll. The air is forced out of the perforations in the guide-roll only at the point where the paper and felt leave that roll to enter on the suction roll. This pressure forces the paper and the felt away from the carrier roll to the suction roll in an efficient manner. On the other hand, when the paper and felt have passed around the suction roll and are about to leave the guide roller *l'* it is necessary to again force the felt and paper away from that roll in order to prevent the trouble previously mentioned. This is done in a manner similar to that described in connection with roll *l* except that the air pressure is applied at a different point. By the apparatus described it is seen that the felt and the paper are carried to and from the suction roll in a fixed manner which will prevent any breakage of the paper which would otherwise result from passing the felt and paper over a suction roll from areas of low and high pressure.

The specific operation of the suction roll will now be described.

The horizontal pipe *u* is connected to a suitable suction producing apparatus and the communication of this pipe with the pipe *m* and the two horizontal extensions of the latter (see Fig. 3) communicate with the interior of the suction roll *g* thus producing an area of low pressure within that suction roll. In order to prevent the area of low pressure from being destroyed by communication with the atmosphere, it is necessary to provide for the perforations between the tangent points of the two guide rollers *l* and *l'* and this is done as follows:—The two lower side edges of the casting *a* shaped as shown bear directly against the inner face of the roll *g* at said tangent points, the atmospheric pressure is thus allowed to communicate with the upper side of the diaphragm *v* and since the under side of said diaphragm is exposed to an area of low pressure, the atmospheric pressure will force said diaphragm downwardly thus carrying the casting *a* downwardly and forcing the edges thereof into firm contact with the inner face of the roll *g* with sufficient pressure to prevent any leakage be-

between the area of low pressure in the roll *g* and the atmospheric pressure. The suction in the pipe *u* will relieve this pressure of the atmosphere against the diaphragm *v* to some extent, due to the fact that the atmospheric pressure will force the pipe *m* acting on its area upwardly, but the area of the diaphragm *v* being large as compared to pipe *m*, the pressure of the atmosphere 10 downwardly will be in excess of that tending to force the diaphragm and casting *a* upwardly.

It will be seen from the description that as the paper passes around the roll *g* on the outside of the felt, the water from the paper will be sucked through the felt to the area of low pressure and pass up the pipe *m* to the pipe *u* and from there out to any suitable point. It is found convenient in building the apparatus to separate the water and air leaving the pipe *u* and force the air back through the pipes *n* of the guide rollers for the purpose described, although it is apparent that this is a mere matter of convenience 25 and not essential to the proper working of the apparatus.

The rotation of the suction roll as well as both guide rollers may be obtained by the passage of the felt and paper which is held 30 sufficiently tight against the rolls to give the required movement thereto. In passing a continuous strip of paper over the suction roll it is clear that only a part of the area of the roll can be used to carry the paper 35 and if the periphery of the roll is perforated to allow the water from the paper to pass through to an area of low pressure it is clear that that area of the roll not carrying paper must be taken care of in a way 40 to prevent trouble or the atmospheric pressure will destroy the area of low pressure.

In addition to the above considerations in the operation of a device embodying applicant's invention there is the problem of 45 leading the paper to and from the suction roll. In the machine described only one felt or carrying medium for the paper is used whereas generally in cylinder machines it is customary to use two felts with the paper 50 carried therebetween. Applicant's apparatus renders one felt only necessary for such a large amount of water is taken from the paper at one time that the paper does not need to travel to and from as many water 55 extracting devices as is now customary. The lower outer edge of the casting *a* as shown defines the area of the roll which is not used to carry paper and the perforations in the roll together with the casting *a* allow 60 the atmospheric pressure to bear on the upper side of the diaphragm *v* which carries and thus forces the casting *a* into its proper bearing function. The pipe *m* is carried by casting *a* and is provided with 65 two horizontal extensions to each side of

said casting to communicate with the area of low pressure. The upper end of pipe *m* slides in a sleeve of casting *a* with a tight fit so that there will be no leakage to pipe *n* from the space above the diaphragm. There 70 may be as many of these pipes as desired, the apparatus illustrated being designed for two. Fig. 2 would show a complete view with these two pipes if another half similar to the one shown were added at the right. 75 The paper takes a rather sharp bend whenever it leaves either roll *l* or *l'* and is liable as stated to break or be injured at these points. The device shown however forces the paper from the roll at the proper points 80 and there is therefore no liability to stick. The apparatus has been shown with a cylinder machine. It is clear however that Fourdrinier machines can be fitted with this suction roll for the paper carrying medium 85 of any description can be led around said roll with the desired results.

The apparatus can be put to many analogous uses to the ones mentioned such as drying cloth or wherever it is desired to 90 cause the rush of air through a continuous moving strip of material.

Applicant has described a specific form of apparatus as illustrating one embodiment of his invention. The invention can be embodied in various other specific forms without departing from the features thereof as defined in the following claims.

What I claim, is:—

1. In a device of the class described, a 100 hollow perforated cylinder mounted to rotate, a suction chamber therein communicating with an exhausting passage, means to guide a paper-supporting web to said cylinder to rotate through a certain arc 105 therewith during which time the perforations of the cylinder in the certain arc are closed by the web, and means to prevent the remaining perforations in the cylinder from establishing communication between the 110 suction chamber and the atmosphere, said means comprising a frictionally engaging device to engage and shut off the arc of the cylinder not covered by the web and including means whereby said frictionally 115 engaging device is held to its duty by air pressure.

2. In a device of the class described, a 120 hollow, perforated cylinder mounted to rotate and surrounding a suction chamber, means to guide a paper-supporting web to said cylinder for rotation therewith through a certain arc during which rotation the moisture in the paper carried by the web is forced into the suction chamber by atmospheric pressure, and a device to prevent the 125 perforations traveling in an arc, other than the one through which the web travels, from communicating with the suction chamber comprising a box suitably supported having 130

for one side a frictional device to engage the surface of the cylinder for the arc last mentioned to establish atmospheric pressure in said box, a diaphragm, one side subject to pressure in the suction chamber and the other to atmospheric pressure, supporting said box and tending to force the same into frictional engagement with the cylinder.

3. In a device of the class described, a hollow, perforated cylinder mounted to rotate, a pipe mounted therein with a communicating passage to the interior of the cylinder whereby a space of low pressure can be obtained, an arc-shaped box-like device, means to force said device into frictional contact with the inner face of the cylinder, as the latter revolves, comprising a diaphragm, a support therefor, means to connect the movable part of the diaphragm and the device, said four last named elements forming a chamber subject to atmospheric pressure due to the device and cylinder, said diaphragm being so mounted that one face thereof is subject to the low pressure space, and the other face to the atmospheric pressure, for the purpose described.

4. In a device of the class described, a hollow, perforated cylinder mounted to rotate, means for obtaining a low pressure space within the cylinder causing the air to rush through the perforations to said space, and means for preventing air reaching said space through said perforations while they

pass through a certain arc comprising a device suitably supported having its edges 35 frictionally engaging the cylinder as it rotates through said certain arc, and a diaphragm supporting said block to maintain said frictional engagement having one face subject to pressure in the box and the other 40 to pressure within the cylinder, and other yielding means to aid in maintaining said frictional engagement.

5. In a device of the class described the combination of a rotatable roll surrounding 45 a suction chamber, perforations through said roll to the chamber, perforated rotatable guide rolls arranged to guide a continuous web to and from said first mentioned roll for rotation therewith through a certain arc, a device to prevent the perforations in the roll from communicating with the suction chamber as the roll rotates through the remaining arc of its circumference, and a device located within each guide roll operable to press against the inner face of said roll at the point where the continuous web leaves the same and adapted to guide a pressure fluid through the perforations at that point to aid the web in leaving, all for 55 60 the purpose described.

CHARLES H. ATKINS.
